UNITED STATES PATENT OFFICE.

GEORGE M. ARRAGG, OF LAWRENCE, MASSACHUSETTS.

SPRING FEELER FINGER.

1,412,595.

Specification of Letters Patent. Patented Apr. 11, 1922.

Application filed April 8, 1920. Serial No. 372,219.

To all whom it may concern:

Be it known that I, GEORGE M. ARRAGG, a citizen of Syria, residing at Lawrence, in the county of Essex and State of Massachusetts, have invented certain new and useful Improvements in Spring Feeler Fingers, of which the following is a specification.

This invention relates to what are known as feeler fingers such as are used in connection with spinning and twisting frames for roving and yarn.

Such fingers have an eye at their free end through which the yarn passes, the friction of the passage of the yarn and the pull of the yarn more or less moving the finger out of its natural position. When a break occurs, or in some cases when a lump passes, the finger is moved abnormally and such movement operates stopping mechanism or alarm mechanism.

The difficulty in the operation of such fingers is that the friction or pull of the yarn is very slight, and it is necessary that such fingers should therefore be very sensitive.

At the same time, on account of the jarring of the machinery, inequalities in the yarn, etc., it is necessary that such fingers should be steady and should not begin to pound or bounce.

My invention is a rocking or elastic feeler finger, and is more specifically such a feeler finger having a guide eye between a bobbin and a yarn guide on a spinning or twisting frame for roving or yarn.

Preferably, the guide eye is located between a bobbin and yarn guiding means but not in direct line therewith.

My construction may be regarded as substantially a shock absorber to take up jars and inequalities whereby the feeling function is sensitively and steadily performed.

In the drawings, Fig. 1 is a side elevation of parts of a worsted cap spinning frame such as shown in patent to George M.

Arragg, No. 1,168,457, January 18, 1916, with my preferred form of rocking member, feeler finger, and guide eye in position.

Fig. 2 is a side elevation, and Fig. 3 a plan view of my preferred form of guide eye and feeler finger.

Fig. 4 is a side elevation of a rocking member with another form of feeler finger and guide eye.

Fig. 5 is a side elevation of another form

of rocking member, finger and guide eye, 55 and Figs. 6 and 7 are similar side elevations of other forms of rocking members, feeler fingers and guide eyes.

Fig. 8 shows my type of feeler finger attached to the stop-motion shown in patent 60 to George M. Arragg, No. 1,168,457 of Jan. 18, 1916.

Fig. 9 is a side elevation showing my form of feeler finger attached to the rocking member, shown in patent to Channing Whittaker, 65 No. 753,338, of March 1, 1904.

Fig. 10 is a diagrammatic side elevation of a modified form of feeler finger attached to another type of electric stop-motion.

Fig. 11 is a detail side elevation of a modification of the form of feeler finger shown in Fig. 10.

In the construction shown in Fig. 1, A represents the rail, part of the frame of a worsted cap spinning frame, B is the bobbin, 75 C, C are the front drawing rolls, 10 are the idler rolls, 11 the bottom back drawing roll, and 12 the top back drawing roll which, as shown in patent to Arragg, No. 1,168,457 of Jan. 18, 1916, is separable from the bottom 80 back drawing roll 11 by means of the lifter 13 actuated by mechanism, indicated generally by M, adapted to separate the back drawing rolls when set in operation by power driven means shown as a vibrator V which 85 as shown in said Fig. 1, causes the mechanism M to separate the back drawing rolls when the rocking member R, pivoted to frame A at 20, is relieved from the pull of the yarn Y by reason of a break or otherwise, and drops to the dotted line position 90 in front of power driven vibrator V. S is a stop to limit the movement of rocking member R.

The back part 21 of the rocking member 95 R is shown as being made of a stiff wire or rod, and the front part F is shown as a flat spring shank having a free end by which is carried the guide eye E through which the yarn passes from the yarn guiding means 100 C, C, to the bobbin B. This is shown as out of the direct line, as in such position there is more pull from the yarn than if it were in a substantially straight line. The front part F is the feeler finger attached to 105 frame A.

The spring shank F shown as a flat spring is cut away on one side at 22 and has at-

tached beyond said cut away part one lip 23 of a guide plate, the other lip 24 being separated from F so that the yarn can slip underneath into cut away part 22 through the slot 26 between the two lips.

This guide plate serves as a slub catcher and to prevent the whiskers or ends of fibre in the roving or yarn from winding around the eye and thus causing trouble.

10 This guide plate is shown as made of metal, with a porcelain eye 25 having a side slot integral with slot 26 and extending down through lip 24 but not beyond it, as it is necessary to leave a space between lip 24 and spring F for the yarn to be threaded.

15 Fig. 4 shows a rocking member R having a pivot block 30 with pivot hole 31, a substantially rigid back part 21 and a front part forming the elastic feeler finger 29 of round 20 spring metal which is turned into a pigtail 32 which serves as a guide eye.

25 In Fig. 5, the rocking member R is pivoted to a part of the frame A at 33 and has a substantially rigid back part 21 and a substantially rigid front part or feeler finger 34 which terminates in a pigtail guide eye 35. Associated with the finger is the spring 36 suitably attached to frame A in such manner that it tends to depress the back part 21 away 30 from stop S and lift the rocking feeler finger at the front.

35 As shown in Fig. 6, instead of the spring 36, I may use the pad of rubber or other elastic material 37 fastened under the pivot brackets 38 in such manner that it tends to depress the back part 21 in the same manner as spring 36.

40 In Fig. 7, the rocking member R is pivoted to the frame A at 40 and has a substantially rigid back part 21 and a substantially rigid front part 41 extending out partway but terminating in an elastic member 42 which ends in a pigtail eye 43, the combination of 41 and 42 forming an elastic feeler finger with an 45 elastic element associated therewith.

45 In Fig. 8, I show my elastic feeler finger applied to the stop-motion such as shown in patent to Arragg, No. 1,168,457 of Jan. 18, 1916.

50 In this view, 50 represents the frame, B the bobbin, C, C front drawing rolls, 51, 51 back drawing rolls, 52 a rocking member, 53 power means for actuating the stop-motion when rocking member 52, falls back to the dotted 55 line position shown in Fig. 8.

55 My elastic feeler finger 54 is shown as a strip of spring steel attached to the rocking member at 55 and terminating in any suitable type of guide eye 56. I also show an adjustable weight 57 carried by feeler finger 54 whereby the parts may be balanced properly.

60 In this view, as in Fig. 1, the dotted lines show the position which the feeler finger would assume, and will assume, when the 65 yarn is not passing through the guide eye.

In Fig. 9, I show my elastic feeler finger attached to the stop-motion for twisting frame shown in patent to Channing Whitaker, No. 753,338, March 1, 1904. In this view, 60 represents the frame, B the bobbin, 70 Y the yarn, 61 the yarn guiding means, and 62 a rocking member pivoted to the frame at 63. It is not necessary to describe any of the parts of this device as they are old and well known except my feeler finger 64. This is 75 shown as a flat strip of spring metal fastened to the rocking member 62 at 65 and terminating in eye E of the same type as that shown in Fig. 1. The yarn in this case is shown as bent at almost a right angle between the yarn 80 guiding means 61 and the bobbin B.

In Fig. 10, I show the application of my feeler finger to an electrically operable stop-motion, in which C, C are the front drawing rolls, 11, bottom back drawing roll, and 12 85 the top back roll, while A is the rail, part of the frame, B is the bobbin and Y is the yarn.

My feeler finger 70 has no tail, but has guide eye E and is formed of a strip of spring steel held to rail A by means of a bolt 71 90 which passes through suitable insulation 72 and is fastened by means of a bolt 73.

From 73 there is an electric connection 74 into the battery 75, and from there an electrical connection 76 to a solenoid T in which 95 travels an armature 77 which terminates at 78 at a point below, beyond and between rolls 11 and 12 out of contact with yarn Y. The parts are so arranged that when the current passes through solenoid T, armature 77 is 100 forced out to the dotted line position, lifting top back roll 12 as shown.

The circuit is made by means of the wire 79 on the solenoid to the contact 80 insulated at 81 and carried by means of an arm 82 by 105 a lifter rod 83 which is shown as having an adjustable knurled nut 84 which serves as a stop to limit the downward movement of finger 70.

As shown by the dotted position of the 110 finger, when the pull of the yarn ceases, the spring rises, making a contact with 80, thence through 71, 73, 74, 75, 76, S and 79, completing the circuit.

When it is desired to doff without actuating the stop-motion, rod 83 is turned, bringing 84 to the dotted position whereby 80 and 81 move back to the dotted line position out of the way of the feeler finger when the tension of the yarn on it ceases and it rises up. 120

125 While it is preferable that my feeler finger should be pivoted, I can, as shown in Fig. 11, use a finger 90 which rests on the insulation 72 and is loose between such insulation and the head of bolt 71.

This finger 90 is shown as made of strip metal with a U spring 91 insulated at 92, fastened to rail A by screw 93.

130 It will be understood that while I prefer to use a feeler finger made of spring metal,

such spring may be regarded as a separate element, as shown in Figs. 5, 6 and 11, associated with the finger.

I claim:

5. 1. In a spinning frame having front drawing rolls, one or more bobbins and separable back drawing rolls, the combination of a rocking member pivoted to the frame, the front part including a finger having a 70
spring shank with a free end, a guide eye carried by the free end of said shank between the front rolls and a bobbin at a point in front of a direct line therebetween whereby the yarn forms an obtuse angle between 75
10 the front rolls and the bobbin with its apex at the guide eye, a guard plate which extends outward from said guide eye having two lips forming a slot open at one end which extends over said shank, one lip being
15 attached to said shank and the other lip being separated therefrom, the back part of the rocking member extending back of the pivot, such rocking member being adapted to rock in a vertical plane, and a stop to limit movement of the rocking member in a vertical plane, with means operative by the pivotal motion of the rocking member to separate the back drawing rolls.
- 20 2. In a spinning frame having front drawing rolls, one or more bobbins and separable back drawing rolls, the combination of a rocking member pivoted to the frame, the front part being a finger having a spring shank with a free end, a guide eye carried by the free end 80
of said shank between the front drawing rolls and a bobbin, at a point in front of a direct line therebetween whereby the yarn forms an obtuse angle between the front 85
25 rolls and the bobbin with its apex at the guide eye, and the back part extending back of the pivot, such rocking member being adapted to rock in a vertical plane, a stop to limit movement in the vertical plane, with mechanism adapted to separate the 90
30 back drawing rolls, and power driven means operative by the action of the rocking member for causing such mechanism to separate the back rolls.
- 35 3. In a spinning frame having front drawing rolls, one or more bobbins and separable back drawing rolls, the combination of a rocking member pivoted to the frame, the front part including a finger having a shank with a free end, a guide eye carried by the free end of said shank between the front 95
40 rolls and a bobbin, at a point in front of a direct line therebetween whereby the yarn forms an obtuse angle between the front rolls and the bobbin with its apex at the guide eye, a guard plate which extends outward from said guide eye having two lips forming a slot open at one end which extends over said shank, one lip being attached to said shank and the other lip being separated therefrom, the back part of the rocking member extending back of the pivot, such rocking member being adapted to rock 100
45 in a vertical plane, an elastic element so associated with each rocking member as to maintain each eye in yielding contact with the roving or yarn, and a stop to limit movement of the rocking member in a vertical plane, with means operative by the pivotal motion of said fingers, a guide eye carried by each finger 105
50 between said rolls and a bobbin, at a point in front of a direct line therebetween whereby the yarn forms an obtuse angle between the front rolls and the bobbin with its apex at the guide eye, a guard plate 110
55 which extends outward from each eye, and means operative by the pivotal motion of said fingers to stop delivery of yarn or roving to said delivery rolls.
- 60 4. The combination with a spinning frame 115 having front delivery rolls and bobbins, of spring fingers pivoted to said frame, each extending out between said rolls and a bobbin, stops to limit the movement of said fingers, a guide eye carried by each finger 120
55 between said rolls and a bobbin, at a point in front of a direct line therebetween whereby the yarn forms an obtuse angle between the front rolls and the bobbin with its apex at the guide eye, and means operative by 125
65 the motion of said fingers to stop delivery of yarn or roving to said delivery rolls.
- 65 5. The combination with a spinning or twisting frame having front delivery rolls and bobbins, of fingers pivoted to said frame 130

each extending out between said rolls and a bobbin, a stop to limit the movement of each finger, a guide eye carried by each finger between said rolls and a bobbin, at a 5 point in front of a direct line therebetween whereby the yarn forms an obtuse angle between the front rolls and the bobbin with its apex at the guide eye, and an elastic element so associated with each finger as to 10 absorb shocks caused by the pull of the roving.

8. The combination with a spinning or twisting frame having front delivery rolls and bobbins, of fingers attached to said 15 frame each extending out between said rolls and a bobbin, a stop to limit the movement of each finger, a guide eye carried by each finger between said rolls and a bobbin, at a point in front of a direct line therebetween 20 whereby the yarn forms an obtuse angle between the front rolls and the bobbin with its apex at the guide eye, and an elastic element so associated with each finger as to 25 maintain each eye in yielding contact with the roving or yarn.

9. The combination with a spinning or twisting frame having front delivery rolls and bobbins, of fingers attached to said 30 frame each extending out between said rolls and a bobbin, a guide eye carried by each finger between said rolls and a bobbin, at a point in front of a direct line therebetween 35 whereby the yarn forms an obtuse angle between the front rolls and the bobbin with its apex at the guide eye, and an elastic element so associated with each finger as to

maintain each eye in yielding contact with the roving or yarn.

10. The combination with a spinning or twisting frame having a bobbin, and means 40 for guiding yarn to said bobbin, of a finger attached to said frame having a free end extending out between said bobbin and said 45 yarn guiding means, a stop to limit the movement of said finger, a guide eye carried by the free end of said finger between said bobbin and said yarn guiding means, at a point in front of a direct line therebetween whereby the yarn forms an obtuse angle between 50 the yarn guiding means and the bobbin with its apex at the guide eye, and an elastic element so associated with said finger as to maintain the eye in yielding contact with the roving or yarn.

11. The combination with a spinning or twisting frame having a bobbin, and means 55 for guiding yarn to said bobbin, of a finger attached to said frame having a free end extending out between said bobbin and said 60 yarn guiding means, a guide eye carried by the free end of said finger between said bobbin and said yarn guiding means but not in direct line therewith, and an elastic element so associated with said finger as 65 to maintain the eye in yielding contact with the roving or yarn, whereby the yarn between said bobbin and yarn guiding means forms an obtuse angle with the apex at such guide eye.

In testimony whereof I have affixed my 70 signature.

GEORGE M. ARRAGG.
